DESIGN FOR A NEGLIGEE

Violet Giovagnoni, New York, N. Y.

Application November 2, 1942, Serial No. 108,670

Term of patent 3½ years

To all whom it may concern:

Be it known that I, Violet Giovagnoni, a citizen of the United States, residing in New York city, in the county of New York and State of New York, have invented a new, original, and ornamental Design for a Neglige, of which the following is a specification, reference being had to the accompanying drawing, forming part thereof.

Fig. 1 is a front view of a negligee showing my new design, and

Fig. 2 is a rear view of the negligee shown in Fig. 1, on a reduced scale.

I claim:

The ornamental design for a negligee, substantially as shown.

VIOLET GIOVAGNONI.
